(57) CLAIM

The ornamental design for a surface mountable light, as shown and described.

DESCRIPTION

FIG. 1 is a perspective view of a surface mountable light, showing my new design;

FIG. 2 is a front elevational view of a surface mountable light;

FIG. 3 is a rear elevational view of a surface mountable light;

FIG. 4 is a left-side elevational view of a surface mountable light;

FIG. 5 is a right-side elevational view of a surface mountable light;

FIG. 6 is a top plan view of a surface mountable light; and,

FIG. 7 is a bottom plan view of a surface mountable light.

The broken lines represent unclaimed structure.
